A cross-sectional diagram of a cylindrical component, likely a piston or cylinder. The internal structure includes a central vertical rod (5), a top piston ring (6), a central bore (10), a lower piston ring (4), and a side bore (3). The side bore is labeled with '11a' at its bottom. The outer boundary of the cylinder is labeled '11b'.

A. M. Waller Jr.

UNITED STATES PATENT OFFICE.

EDGAR H. FREEMAN, OF TRENTON, NEW JERSEY

LAMP-SOCKET.

1,260,360.

Specification of Letters Patent.

Patented Mar. 26, 1918.

Application filed January 6, 1915, Serial No. 797. Renewed February 18, 1918. Serial No. 216,977.

To all whom it may concern:

Be it known that I, EDGAR H. FREEMAN, a citizen of the United States, residing at Trenton, in the county of Mercer and State 5 of New Jersey, have invented certain new and useful Improvements in Lamp-Sockets, of which the following is a specification.

This invention relates to the general subject of lamp sockets and more particularly 10 to a novel construction especially adapted to lamps of large voltage and capacity.

A primary object of the invention is to provide a socket constructed with special reference to strength, rigidity and compactness of parts thereby rendering the same useful with lamps of the character above pointed out, though susceptible of general application to all sizes of incandescent lamps.

20 Another object is to provide novel and practical means for holding the socket parts in assembled relation. That is to say, the present device contemplates the use of combined fastening and current conducting elements, which not only serve as means for locking together with interior socket parts, but also as a clamping means for locking the cap and shell together, and furthermore carry the current from the wire terminals to 25 the plug contacts. This construction is particularly advantageous, since the mere act of loosening these combined fastening and conducting elements separates the entire socket.

30 As a further object the invention proposes to utilize stout and substantial parts that are easily and economically manufactured and readily assembled. In this latter connection, it may be noted that the construction 40 of the interior parts of the socket are such that the mere assembling or bringing together thereof, centers and alines the parts for the reception of the binding or fastening elements thereby greatly facilitating the 45 assembling operation.

Another object of the invention is to provide a rigid and tight fitting connection between the cap and shell members to make a substantially waterproof socket, thereby 50 adapting it to a wide range of uses, and can be used in exposed places as well as an interior fitting.

With the above and other objects in view which will more readily appear as the 55 nature of the invention is better understood, the same consists in the novel construction,

combination and arrangement of parts hereinafter more fully described, illustrated, and claimed.

A preferred and practical embodiment of 60 the invention is illustrated in the accompanying drawings, in which—

Figure 1 is a vertical sectional view of the assembled socket.

Fig. 2 is a view similar to Fig. 1 showing 65 more plainly the combined fastening and current carrying screws in detail.

Fig. 3 is a bottom plan view of the cap and insulating base therein.

Fig. 4 is a top plan view of the shell portion of the casing showing the plug contact block.

Fig. 5 is a cross section of the cap on the line 5—5 of Fig. 3.

Similar reference characters designate 75 corresponding parts throughout the several figures of the drawings.

In carrying out the invention, it is proposed to follow the general outline and conventional design of standard lamp sockets, 80 and with this end in view, the invention contemplates a metallic socket casing including the main shell or body 1, and a cap member 2 having the usual opening 3 therein for the reception of the line wires. 85

The socket cap is provided within the top part thereof, adjacent the wire opening 3, with the stationary nut members 4. These may be formed as shown, that is, from a plate stamping fastened to the crown piece 90 of the cap, and having opposite folded portions whose terminals are threaded at 4^a to provide the nuts. The largest diameter of the cap is at its peripheral edge 5 which telescopically receives the coupling flange 6 95 of the shell 1. Adjacent the said flange 6 on the shell body 1 is formed a continuous external bead 7 which provides an annular internal holding groove 8, the purpose of which will hereinafter more fully appear. 100

Referring further to the cap member 2, it will be noted that the same has fitted therein a circular disk-like base block 9 which may be made of porcelain or other insulating material suitable for this purpose. This 105 block not only constitutes a substantial base for the wire terminals and effectively insulates the cap according to standard requirements, but also constitutes a holding member to which couples the other interior parts of the socket, as will be more readily apparent as the description proceeds in de-

tail. The said block 9 is rigidly mounted in the cap by means of suitable fastening screws 10 or equivalent fastening elements, coöperating with the stationary nut members 4, and is also provided with suitable line-wire terminal plates 11 held by screws 11^a on opposite sides of the central wire receiving opening 12 which registers with the opening 3 in the cap, thereby affording 10 an unobstructed passage for the line-wires into the socket.

In addition to having the usual binding screws 12^a for holding the line-wires, the terminal plates 11 are provided with screw 15 receiving openings *a*, thereby constituting nut plates for the combined current carrying and fastening elements hereinafter referred to. The circumferential side wall of the block 9 is formed with diametrically opposite guiding and alining recesses 13 which 20 register with similarly arranged fastening clip recesses 14 in the insulating plug-contact block 15 in the shell 1.

The insulating block 15 has secured there- 25 to in the recesses 14, the angular flanged spring fastening or retaining clips 16 which are adapted to be sprung into the annular recess 8 on the shell body to always hold the block in proper position within the shell. 30 Not only do these clips hold the block 15 in the shell, but they also coöperate with the recesses 13 on the block 9 to properly and easily aline the two insulating blocks.

The rigidity and compactness of the 35 socket is increased by the combined conducting and fastening screws 17 and 18 which pass through the openings 19 in the body of the block 15 and thread into the openings *a* on the terminal plate 11 herein- 40 before referred to. These screws, therefore, serve to strongly couple the two blocks 9 and 15 together, and because the latter are respectively connected to the cap 2 and shell 1, these two parts of the socket are also, 45 firmly and rigidly united by said screws 17 and 18. In this connection it will also be apparent that the parts just referred to as being coupled by these screws can be separated by the mere act of loosening the same, 50 thereby providing a quick and easy means for taking the socket apart.

It will therefore be apparent that the interior socket parts are held rigidly and tightly in place, since the block 9 is rigidly 55 fastened to the cap and the block 15 is interlocked with the shell, and then both are rigidly fastened together by means of the screws 17 and 18.

One face of the cylindrical insulating 60 block 15 is formed with suitable pockets 20 to provide chambers for the terminal plates 11 when the blocks are assembled, and at the same time effectively house the exposed end 65 of the terminal wires, while the other face is recessed as at 21 and carries the ordinary

screw shell contact 22 and also carries the usual center plug contact 23 which is held in position by the screw 24. The said center plug contact 23 is provided with a conductor plate 25 through which passes the fastening 70 and current carrying screw 17, and the screw shell contact 24 has secured thereto an ordinary bridge plate 26 through which the other of the fastening and current carrying screws 18 passes. It will thus be apparent that the screw 17 is in electrical contact with one of the wire terminal plates 11 at one end, and in electrical contact at the other with the center plug contact 23 through the plate 25, while the screw 18 is 80 in electrical contact with the other of the wire terminal plates and with the bridge plate 26 of the screw shell contact 24. For the purpose of properly insulating the socket casing from the screw shell contact 85 24, there is preferably interposed between these members a fiber insulating sleeve 27.

With the insulating blocks mounted in the cap and shell, as described, it is only necessary to fit the cap member onto the shell so that the alining recesses 13 in the block 9 receive the fastening clips 16, thus bringing the openings 19 in the block 15 into alinement with the threaded openings on the wire terminal plates 11. In addition 95 to alining the openings 19 with the holes *a* in the wire terminal plates, this engagement between the cap member and shell member also brings the wire terminal plates 11 over the pockets 20 in the face of the block 15, 100 thereby placing these terminal plates in separate chambers which effectively prevent stray ends of the line-wires from coming in contact and causing a short circuit.

When the cap member and shell member 105 are in their assembled relation, they may be secured together by tightening up the combined current carrying and fastening screws 17 and 18. This action draws the cap and shell member together and forms a tight 110 joint therebetween, thus producing a substantially waterproof socket.

From the foregoing description, it is thought that the many features and advantages of the present invention will be readily apparent, and it will of course be understood that various changes in the form, proportion and minor details of construction may be resorted to without departing from the spirit of the invention or scope of the 120 appended claims, and without sacrificing any of the advantages thereof.

I claim:

1. A lamp socket including a divided 125 socket interior, the separate parts of which respectively carry the line wire terminals and the lamp terminals, the shell member, the cap member, means for fastening one part of the socket interior in the shell member and the other part of the socket interior 130

in the cap member, and current carrying screws connecting the line terminals with the lamp terminals and thereby also constituting the fastening means for the cap and shell.

- 5 2. A lamp socket including the shell member, a cap member, an insulating base fastened to the cap member and carrying the wire terminals, a block fastened to the shell 10 member and carrying the lamp terminals, and current carrying screws connecting the lamp terminals and wire terminals and thereby also constituting means for separably locking together the cap and shell.
- 15 3. A lamp socket including the shell member, the cap member, an insulated base fastened to the cap member and carrying the wire terminals, an insulating block fastened to the shell member and carrying the lamp 20 terminals, and current carrying screws connecting the lamp terminals and the wire terminals and thereby also forming a separable locking connection between the cap and shell.
- 25 4. A lamp socket including the shell member and cap member, an insulating base block fastened to the cap member and having alining notches, terminal plates carried by the said block, a plug contact block, 30 means carried by said plug contact block for engaging the shell and registering in said alining notches of the base block, a center plug contact carried by said plug contact block, a screw shell contact also carried thereby, and separate current carrying screws connecting the base block and contact block and thereby separably locking together the cap and shell, said current carrying screws connecting with one of the wire

terminal plates, the center plug contact, and screw shell contact respectively. 40

5. A lamp socket including the shell member and cap member, nut plates carried by said cap member, an insulating base block secured to said nut plates and having diametrically opposite alining recesses, wire 45 terminal plates carried by the cap, a plug contact block, flanged retaining clip members carried by the latter block and engaging with the shell, said clip members also 50 engaging within the diametrically opposite recesses of the base block in the cap, and current carrying screws connecting with the electrical terminals on both the base block and the contact block and thereby locking 55 the cap and shell elements together.

6. A lamp socket including a shell member having an upstanding peripheral flange at one end, an external bead adjacent said flange and presenting an interior annular 60 groove, a plug contact block in said shell and having means for engaging with the groove therein, a cap member adapted to telescopically receive the said flange of the shell member, a base block carried by the 65 cap member and having wire terminal plates, and current carrying screws connecting with the electrical terminals on both the base block and the contact block and thereby locking the cap and shell elements together. 70

In testimony whereof I hereunto affix my signature in the presence of two witnesses.

EDGAR H. FREEMAN.
